UNITED STATES PATENT OFFICE.

LESLIE STEVENS, OF GLEN RIDGE, NEW JERSEY.

HAT-SHAPING APPARATUS.

1,392,605.

Specification of Letters Patent. Patented Oct. 4, 1921.

Application filed September 14, 1917. Serial No. 191,371.

To all whom it may concern:

Be it known that I, LESLIE STEVENS, a citizen of the United States, residing at Glen Ridge, in the county of Essex and State of New Jersey, have invented certain new and useful Improvements in Hat-Shaping Apparatus, fully described and represented in the following specification and the accompanying drawings, forming a part

10 of the same.

This invention relates to apparatus for shaping hats. The invention has been made especially with the idea of providing an apparatus for blocking fiber or palm hats, such as Panama, Bangkok and Porto Rican hats, and the invention aims to provide apparatus whereby hats of this kind may be blocked or shaped rapidly and without harm to the exposed surface thereof and with 20 which the blocking or other shaping of hats may be done as well if not better than with the commonly used and relatively slow and expensive methods of hand shaping. The invention is not, however, limited in its 25 use to the blocking or shaping of hats of this kind, but is useful for blocking and other shaping of hats of various other materials.

Fiber, palm and straw hats cannot be blocked or shaped between coacting rigid die 30 faces without injury to the appearance of the hat, resulting from the crushing of the surface of the fabric through the contact and pressure of the die faces. Such pressing contact of rigid dies is also harmful 35 to various other hat materials causing spotting, glazing, mirroring, or otherwise injuring the surface of the material. One of the objects of the present invention is to provide a shaping apparatus which will effect 40 the desired shaping of the hats without marring the appearance of exposed surface portions thereof. This result is secured by so constructing the shaping apparatus that the hat is shaped without having any rigid 45 pressing or die faces come into contact with the principal outer or exposed portions of the material, and an important feature of the invention lies in the provision of a shaping member of flexible or yielding material 50 for coacting with a rigid shaping form to shape the hat material thereagainst, such

flexible shaping member being most desirably made of canvas or other suitable porous as well as flexible sheet material, so that when the hat material is pressed thereby 55 against a heated form or die steam and vapor from the moistened material will be free to escape and rapid drying will result.

It is also desirable in blocking hat bodies of fiber and other materials that the material 60 be stretched or pulled out over the form. In hand blocking, the hat bodies are so stretched or pulled over the form, and it is largely on this account that hand blocked hats are so much better than the ordinary 65 machine blocked hats. There is special difficulty in securing this pulling or stretching action when blocking a hat body made with a finished edge as is the case with Panama, Bangkok and other fiber or palm bodies, 70 since the whole of the body remains in the finished hat and there is no excess or waste portion at the edge which can be gripped by ordinary gripping devices. The present 75 invention aims to and does provide an apparatus whereby the material of the hat body being shaped is given the desired outward stretch or pull, and which operates equally well on a body having no excess edge portion to be discarded after the hat is 80 blocked as it does on a body having such excess portion.

The invention also includes other features contributing to the successful operation of the apparatus and economy and simplicity of 85 its construction, all as hereinafter set forth and described and specifically pointed out in the claims.

A full understanding of the invention can best be given by a detailed description of apparatus embodying the invention in an approved form, and such a description will now be given in connection with the accompanying drawings, in which:—

Figure 1 is a perspective view of a hat 95 blocking or shaping machine embodying the invention, a small part of the frame being broken away;

Fig. 2 is a central vertical sectional view on a larger scale of the upper portion of 100 the machine shown in Fig. 1, the solid lines showing the device in operative position and

the dotted lines showing the same in inoperative position;

Fig. 3 is a horizontal sectional view taken on line 3—3 of Fig. 2; and

5 Figs. 4 and 5 are detail sectional views showing crown forms of other shapes.

Referring to the drawings and first more particularly to Fig. 1, the various operative parts of the machine shown are carried by a 10 hollow pedestal 10 which is provided at its upper end with a table 11 to the opposite sides of which are secured frames 12 and 13. The table 11, as will appear more fully hereinafter, serves as a support for the lower die 15 or shaping member and the heating means therefor. For supporting the upper shaping member or means, there is provided a cross-head 14 which is carried by two vertical sliding rods 15, the cross-head being 15 mounted so as to be vertically adjustable on the rods 15, as by being mounted between nuts 16 and 17 threaded on the upper portion of each of the rods 15. The rods 15 are secured at their lower ends to a horizontal cross-bar 18 extending through a vertical slot 19 in the pedestal 10. The cross-bar 18, the rods 15 and the cross-head 14, together with the parts carried by the cross-head, are 20 normally held in their raised position by means of springs 20, and are moved downwardly against the tension of the springs 20 by means of a pedal 21 which is pivotally connected, as by links 22, to spaced arms 23 pivotally mounted on a horizontal shaft 24 25 which is supported at its ends in the side frames 12, 13, the free end of the arms 23 being pivotally connected to arms 25 pivotally mounted on the cross-bar 18. The springs 20, as shown, are connected at their 30 lower ends to projections 26 on opposite sides of the pedal 21, and at their upper ends they are connected to the under side of the table 11, the projections 26 being arranged forwardly of the pivot 27 of the pedal 21 so as 35 to exert a tendency to raise the latter and through it the cross-bar 18. A hand lever 29 is also provided by which the cross-head may be lowered, but which is especially intended for applying greater power to the cross-head 40 at the end of its downward movement and for locking it after it has been given its full downward movement. This hand lever is secured to a horizontal shaft 30 mounted in a bearing on the base of the pedestal, which 45 shaft is provided with an arm 31 to which is pivotally connected a link 32 which is pivotally connected at its opposite end to the 50 pedal 21. This construction provides a toggle between shaft 30 and the pedal 21 which 55 is straightened out so as to force the pedal downwardly when the lever 29 is thrown 60 forwardly and downwardly, and the parts are so proportioned that when the members of the press have been brought into operative 65 relation to each other, the toggle has passed

its dead center position and the tendency of the springs 20 is then to hold the device locked in position, further movement of the toggle being prevented as by engagement of a projection 31' on the arm 31 with the pedestal 10. By upward movement of the lever 29 from its lowest position, the toggle is broken so that the springs may again act to lift the pedal and the upper member of the press.

70 The general construction of the press with its operating pedal and hand lever and connections, as above described, is old and in itself forms no part of the present invention.

75 The shaping or die member against which the hat body or material is shaped, and which in the machine shown is the lower shaping member, will be shaped according to the shape to be given to the hat or the hat brim or crown, and might be of any suitable 80 construction for coöperating with other parts of the apparatus. The invention includes, however, features relating to the construction and mounting of this shaping member which are most desirably used and which are 85 embodied in the construction shown. In the apparatus shown, which is adapted for shaping the crown and brim of a complete hat, the lower shaping member is a two-part form comprising an imperforate metal crown 90 form 34 and an imperforate metal brim form 35, both of these forms being supported by a hollow metallic member 36. The crown form 34 as shown is hollowed out, and the supporting member 36 is provided with an 95 upwardly extending hollow tapered portion 100 or dome 37 arranged to project into and provide a seat for the crown form. In order to economize in the use of material and also to save labor in fitting the crown form 105 to the supporting member 36, the crown form may be provided with inwardly extending ribs or lands 38 shaped to engage the sides of the dome 37 when the form is in 110 position. The brim form rests upon a flat 115 supporting face 39 of the support 36 and is held in proper relation to the crown form by its engagement with the upwardly extending portion of the support, and its inner portion serves as a support for the lower 120 edge of the crown form. The forms shown are suitable for blocking a hat of a shape commonly used for Panama hats, but forms of other shapes may obviously be substituted for either or both of those shown, the 125 use of separate crown and brim forms making it possible to block hats to a great variety of shapes without requiring a complete hat form for each change in shape or proportion of crown or brim. The support 36 is made hollow so as to provide an internal chamber 40 extending upwardly into the crown part 37 of the support and laterally in the brim part of the support, to receive, as by a pipe or other conduit 41, steam 130

or other heating fluid. With this construction, the member 36 not only serves to support the crown and brim forms in proper position in the press, but it also serves when 5 steam or other heating fluid is admitted thereto as a means for heating both these forms. The member 36 may be secured to the table 11 by any suitable fastening means, such as the bolts 42.

10 The upper shaping member or means, hung from the cross-head 14, includes an annular flexible brim shaping member 43 formed of a sheet of flexible material secured at its outer edge to a carrying ring 15 44 formed most desirably of upper and lower ring members secured together, as by means of screws, as indicated in the drawings, and between which the peripheral portion of the sheet of flexible material is secured. For 20 securing all the advantages of this feature of the invention, the sheet material of which the annular flexible member is formed should be porous, and should be flexible not only transversely to its plane but also in 25 its plane, that is, as it may be termed, universally flexible, and should have a yielding friction surface. Ordinary canvas of a suitable weight and strength meets these conditions and is the best material that I found 30 for the purpose. It is sufficiently porous to permit the free escape of steam and vapor for securing rapid drying of moistened hat fabric on a heated form, it has sufficient universal flexibility to accommodate itself 35 to shaping forms or dies of various shapes or configurations when strained thereagainst by the downward movement of the means by which it is carried, and has a surface which when it is stretched outward over the 40 form while bearing against the hat material on the form will sufficiently grip the material to effect the desired outward pulling or stretching of the hat material over the form without spoiling its surface appearance.

45 The carrying ring 44 of the flexible member 43 in the construction shown is supported from the cross-head by vertical rods 46 which extend upward through radial slots 47 in the cross-head, the upper ends of the 50 rods being threaded and being secured to the cross-head by means of nuts 48 and 49 which provide means for adjusting the rods and the shaping member 43 vertically with relation to the cross-head, and for holding 55 the same in proper adjustment. The carrying ring 44 is of a size to pass outside of and clear of the brim form 35. The flexible shaping member 43 is cut away in the center or made of annular form so that it may pass 60 down around the crown form and the band ring hereinafter described, and its inner periphery is most desirably of such size and shape as to fit closely about said band ring, and when formed of canvas or other uni- 65 versally flexible and slightly extensible ma-

terial, it is provided at its inner edge with reinforcing means, such as a non-extensible strand 50 of wire or other suitable material around which the fabric forming the member 43 is secured.

70 For stretching the material over the crown form and forming the head band, or sharply bending the material at the juncture of the crown and brim portions of the hat, a band ring 51 is provided hung from the cross-head 14 by rods 52 arranged to move vertically in slots 47 of the cross-head. Springs 53 interposed between the cross-head and a guide member 54 resting on the band ring tend to hold the band ring and the rods 52 75 in their lowermost positions, downward movement of the rods and of the band ring being limited, as by nuts 55 on the upper ends of the rods. The guide member 54 is held in place on the band ring by the rods 52 and springs 53 and has laterally extending portions fitting for vertical sliding movement on two of the rods 46, to thereby hold the band ring against lateral displacement, without interfering with the relative vertical movement between the band ring 51 and the brim shaping member 43. The band ring is made with its inner lower edge of a size and shape to fit loosely about the lower portion of the brim form, leaving a space between it and the lower edge or portion of the brim form for the material of the hat body but which is most desirably equal only to something less than the normal thickness of the material of the hat body, 90 so that when the band ring is moved downward about the crown form with a body positioned on the form, the material of the body will be engaged by the edge of the band ring somewhat before the band ring reaches its lowermost position and will by 95 the further downward movement of the band ring be pulled or stretched downward somewhat over the crown form and forced tightly into the angle between the crown and brim form. The lower edge or end of the band ring is made narrow so that only a narrow portion of the brim portion of the hat directly adjacent the band will be engaged by it. The band ring is most desirably extended upward 100 as shown to serve as a shield for protecting the crown of a hat being blocked against being soiled. It is desirable in order to avoid marring the surface of the 105 hat crown and in order to permit free escape of steam and vapor from the moistened material when the hat is being shaped on a heated form, that the inner face of the band ring thus upwardly extended shall not 110 come in contact with the hat material except at and close to the band angle. When the crown form is substantially inclined inward and upward, as in the case with the 115 form shown in the drawings, the inner walls 120 of the band ring are inclined outward and upward, as shown, so that the inner face of the band ring is inclined outward and upward, as shown, so that the inner face of the band ring thus upwardly extended shall not 125 come in contact with the hat material except at and close to the band angle. When the crown form is substantially inclined inward and upward, as in the case with the 130 form shown in the drawings, the inner walls

of the band ring may be formed parallel or even somewhat inwardly inclined, but for operating with crown forms having sides substantially parallel or only very 5 slightly inclined, it is desirable to form the interior walls of the band ring outwardly and upwardly inclined, or slightly flaring, as shown.

In shaping hats of woven material, and 10 especially Panama and other hats which have a distinctly marked crown or tip center, it is very desirable that the hat body shall be shaped with such woven center accurately positioned. In order to insure such 15 accurate positioning of the woven center in the finished hat and to avoid displacement of the body in shaping it on the form or die in my apparatus or any similar apparatus, I provide means for first clamping the 20 tip center of the hat body to the crown form before the body is pulled over and shaped on the form. Such means in the construction shown in Figs. 1 and 2 consists of a small clamping piece 56 carried by a short 25 rod 57 extending vertically through an opening in the guide member 54 and pressed downward from the guide member by a spring 58, its downward movement being limited by a stop 59. The length of the rod 30 is such that when the cross-head 47 is moved downward the clamping piece or head 56 will come into operative position to clamp the tip of the hat body to the crown die before the band ring reaches its operative 35 position. In addition to serving its purpose as a clamping device, the clamping piece or head 56 also acts to flatten out the extra thickness or bunch of material at the center of the crown tip.

40 The parts above described are so arranged and adjusted that on downward movement of the cross-head, the clamp 57 first engages the center of the hat. After this the band ring and still later the brim forming member 43 come successively into operation, the 45 spring 58 yielding to permit further downward movement of the band ring when the clamping piece 56 is in operative position and the springs 53 yielding to permit further 50 downward movement of the cross-head and brim forming member after the band ring has reached operative position.

The tip clamping piece need not, of course, be of the small form shown in Figs. 1 and 2 55 for engaging only the tip center, although in shaping a crown with a plain tip portion this is desirable in order to avoid unnecessary contact of any clamping means with the hat material. When the tip of the hat 60 is to be formed with a recess, as in case of hats having telescoped tips or creased tips, the clamping piece is desirably formed as a tip block or plate shaped according to the desired shape of the crown tip so that 65 the telescoped or creased hat will be com-

pletely blocked or shaped with the one operation of the press. Such clamping pieces are illustrated by Figs. 4 and 5, Fig. 4 showing a clamping piece 56^a in the form of a tip block or plate for coöperating with a telescope tip crown form 34^a for shaping the hat with a telescope tip, and Fig. 5 showing a clamping piece 56^b formed for coöperating with a crown form 34^b having a creased, or longitudinally recessed, tip. The telescoping clamping piece 56^a might of course be cut away as indicated by dotted line *a'* in Fig. 4 so as not to make contact with the whole tip portion of the hat body, but merely to press the material down into the 70 annular groove of the crown form and also, most desirably, to press against the extra thickness or bunch of material at the tip center in order to flatten the same. So also, the creasing clamping piece 56^b might 75 be cut away as indicated by dotted line *b* so as to make contact with the material only at the bottom of the crease.

In shaping or blocking a Panama hat, for 80 example, by means of the machine, the properly damped hat body *a* is placed over the heated lower shaping member or die with its tip center properly centered on the crown form. The cross-head 14 is then lowered sufficiently to cause the clamping 85 piece 56 to clamp the tip of the body against the crown form. Then before the clamping ring 51 is moved farther down into operative position, the hat body is pulled out properly over the crown form, and the cross-head is then further lowered to cause the clamping ring to move downward to draw the body smoothly down over the crown form stretching it tight against the 90 surface of the form and finally clamping the material of the hat body against the brim form at the line of juncture of the crown and brim parts of the body, thereby forming the desired sharp bend at the band. Then before the flexible brim-pressing member 43 is brought into operation by further 95 downward movement of the cross-head, the brim portion of the hat body is pulled out over the brim form by the operator or operators as may be necessary, and when the brim is in suitable position, the cross-head is given its further and final downward movement by which the flexible brim pressing and stretching member is drawn downward to the 100 position shown by full lines in Fig. 2 to press the brim and pull it out smoothly and tightly against the heated brim form. The action of this flexible brim pressing device is not merely to press the brim smoothly against the brim form or die, but it also acts, as it 105 is itself subjected to the pull or strain of the last of the downward movement of its holding ring 44, to pull and stretch the material of the hat brim slightly outward over the 110 brim form. This final pulling action, or 115 120 125 130

outward stretching action, is of great advantage in securing the desired smoothness and proper shaping of the brim on the brim form.

- 5 The adjustment of the operating parts of the press should be such that when the cross-head 14 has been given its full downward movement to perform the above operations, the toggle 31-32 moved by the hand lever 29
 10 will have passed the dead center to lock the press in its closed position so that the blocking or shaping devices will then remain in position to hold the hat clamped and pressed against the die. When so held, the hat body
 15 will dry out rapidly since the outer surface of the crown is exposed to the air circulating within the band ring and practically all of the brim is covered merely by the porous flexible pressing member 43. When sufficiently dried, which will ordinarily be after only a few minutes, the cross-head may be raised and the blocked and dried hat removed from the press. As the crown, except for the small portion engaged by the
 20 clamping piece 56 and a narrow portion at the band, and the brim, except for the small portion adjacent the base of the crown which is engaged by the edge of the band ring 51, have not been engaged by any rigid member or part, their outer surfaces will not have been flattened or otherwise damaged.

The operation of blocking a hat with my apparatus as above described may with most shapes of dies be performed readily and quickly by a single operator, and the whole operation may be carried through much more quickly and with results equally as good, if not better, than with the old methods of hand blocking.

- 40 It will be understood that the invention is not limited to the exact construction and combination of parts shown and to which the foregoing description has been largely confined, but that it includes changes and modifications thereof within the claims, and that parts and features of the invention as claimed may be used independently of other features shown in other combinations.

What is claimed is:

- 50 1. In a shaping machine, the combination with a press having opposed supporting members and means for moving one of said members toward and from the other, of a form carried by one of said supporting members, and shaping means carried by the other supporting member comprising both a shaping member of flexible and porous material and means for tensioning said shaping member over said form to stretch thereon the material being shaped.

2. In a shaping machine, the combination with a press having opposed supporting members and means for moving one of said members toward and from the other, of a form carried by one of said supporting

members, and shaping means carried by the other supporting member comprising an annular shaping member formed of flexible sheet material and having a substantially inextensible inner edge and means engaging the outer edge of said shaping member and operating to pull said member outwardly over said form to shape thereon the material being shaped.

3. In a shaping machine, the combination with a press having opposed supporting members and means for moving one of said members toward and from the other, of a form carried by one of said supporting members, means for heating said form, and shaping means carried by the other supporting member comprising a shaping member formed of flexible and porous sheet material and means for tensioning the flexible and porous material over the form to shape thereon the material being shaped.

4. In a hat shaping machine, the combination with a press having opposed supporting members and means for moving one of said members toward and from the other, of a brim form carried by one of said supporting members, and shaping means carried by the other supporting member comprising a sheet of flexible material and means caused by the approaching movement between said supporting members to tension said sheet over the brim form to shape the hat material thereon.

5. In a hat shaping machine, the combination with a press having opposed supporting members and means for moving one of said members toward and from the other, of a brim form carried by one of said supporting members, and shaping means carried by the other supporting member comprising a flexible member for coöperating with the brim form having a friction surface adapted to engage and grip the hat material on the brim form and means for causing said member to pull the hat material outward on the form.

6. In a hat shaping machine, the combination with a press having opposed supporting members and means for moving one of said members toward and from the other, of a brim form carried by one of said supporting members, and shaping means carried by the other supporting member comprising a sheet of flexible material and a carrier to which the edge of said sheet is secured and whereby the sheet is pulled outward over the brim form to stretch the hat material outward on the form.

7. In a hat shaping machine, the combination with a press having opposed supporting members and means for moving one of said members toward and from the other, of a brim form carried by one of said supporting members, and shaping means carried by the other supporting member comprising means

for clamping the hat material adjacent one edge of the brim form and a shaping member formed of flexible sheet material and means for tensioning the flexible material over said brim form to shape the hat material thereon.

8. In a hat shaping machine, the combination with a press having opposed supporting members and means for moving one of said members toward and from the other, of a hat shaping form comprising a crown part and a brim part carried by one of said supporting members in fixed relation to each other, and shaping means carried by the other supporting member comprising a band ring for stretching the hat material over the crown part of said form and means mounted to come into operation after said band ring to stretch the brim portion of the hat material outwardly over the brim part of said form.

9. In a hat shaping machine, the combination with a press having opposed supporting members and means for moving one of said members toward and from the other, of a hat shaping form comprising a crown part and a brim part carried by one of said supporting members, and shaping means carried by the other supporting member comprising a clamping member for pressing the tip of a hat body against the crown part of said form, a band ring mounted to come into operation after said clamping member to stretch the hat material over the crown part of said form, and means mounted to come into operation after said band ring to stretch the brim portion of the hat material over the brim part of said form.

10. In a hat shaping machine, the combination with a press having opposed supporting members and means for moving one of said members toward and from the other, of a form carried by one of said supporting members, said form having an indented tip portion, and shaping means carried by the other supporting member comprising means for shaping the hat body against said form and a clamping member for indenting the tip of the hat body and pressing the same against said form to shape the tip and hold the hat body in position for the shaping operation.

11. In a hat shaping machine, the combination with a press having opposed supporting members and means for moving one of said members toward and from the other, of a hat shaping form carried by one of said supporting members comprising a crown part and a brim part in fixed relation to each other, and shaping means carried by the other supporting member comprising a yieldingly mounted clamping member for pressing the tip of the hat body against the crown part of said form, crown shaping means for stretching the crown portion of

the hat body over the crown part of the form, and brim shaping means for stretching the brim portion of the hat body over the brim part of said form, said clamping member being mounted to come into operation ahead of said crown shaping means.

12. In a hat shaping machine, the combination with a press having opposed supporting members and means for moving one of said members toward and from the other, of a hat shaping form carried by one of said supporting members and comprising a crown part and a brim part in fixed relation to each other, means controlled by the movement of the movable supporting member for stretching the crown portion of a hat body over the crown part of said form, said means being formed to engage the hat body only at and near the band portion thereof, and means for stretching the brim portion of the hat body outwardly over the brim part of said form after the crown portion has been stretched.

13. In a hat shaping machine, the combination with a press having opposed supporting members and means for moving one of said members toward and from the other, of a hat shaping form carried by one of said supporting members and comprising a crown part and a brim part, means controlled by the movement of the movable supporting member for stretching the crown portion of the hat body over the crown part of said form, said means being formed to engage the hat body only at and near the band portion thereof, and brim shaping means comprising an annular shaping member formed of flexible sheet material and means for pulling said member against the brim part of said form and outwardly to stretch the brim portion of the hat body against the brim part of said form.

14. In a hat shaping machine, the combination with a press having opposed supporting members and means for moving one of said members toward and from the other, of a hat shaping form carried by one of said supporting members and comprising a crown part and a brim part, and shaping means carried by the other supporting member comprising a band ring for stretching the crown portion of the hat body over the crown part of said form, said band ring being extended to inclose the crown part of said form and having its inner wall spaced away therefrom except at the band, and brim shaping means comprising an annular shaping member of porous flexible sheet material extending outward from the band ring and a carrier to which the outer edge of said member is secured and by which the outer edge of said member is forced downward to stretch the brim portion of the hat body against the brim part of said form, said band ring being yieldingly mounted to

come into operation before said brim shaping means.

15. In a hat shaping machine, the combination with a press having opposed supporting members and means for moving one of said members toward and from the other, of a hat shaping form carried by one of said supporting members and having a continuous surface comprising a crown part and a 10 brim part meeting at an angle, and shaping means carried by the other supporting member comprising means for forcing the hat material into the angle at the juncture of the crown and brim parts of the form and 15 clamping it against the form along the line of the apex of said angle of juncture, a brim shaping member of flexible sheet material, and a carrier to which the edge of said brim-shaping member is secured and where- 20 by said member is stretched outwardly over the brim part of the form to press the hat material against said brim part.

16. In a hat shaping machine, the combination with a press having opposed supporting members and means for moving one of said members toward and from the other, of a hat shaping form carried by one of said supporting members comprising a crown part and a brim part, and shaping means 25 carried by the other supporting member comprising means for forcing the hat material against the form at the line of juncture of the brim and crown parts thereof, a brim shaping member of flexible sheet 30 material, and a carrier to which the edge of said brim-shaping member is secured and whereby said member is stretched outwardly over the brim part of the form to press the hat material against said brim 35 part, said brim shaping member and carrier being mounted to come into operation after said forcing means.

17. Hat shaping apparatus, comprising coacting shaping members, and means for 40 causing a relative approaching movement between said members, one of said members comprising a brim form and heating means therefor, and the other of said members comprising a sheet of porous flexible material 45 and carrying means therefor whereby by the approaching movement between said members said sheet of flexible material is pulled over said brim form to press and stretch the hat material thereagainst.

55. 18. Shaping apparatus, comprising a form, means for heating said form, a shaping member for coacting with said form formed of flexible woven sheet fabric, and means for causing an approaching move- 60 ment between said form and said shaping member and for stretching said member over said form.

19. Apparatus for shaping hats, comprising a brim form, means for coacting with 65 said brim form comprising an annular band

of porous flexible sheet material, tension-resisting means applied to the inner edge of said band and a carrying member to which the outer edge of said band is secured, and means for causing a relative approaching 70 movement between said form and said carrying member.

20. Hat shaping apparatus, comprising in combination a brim form, a shaping member formed of flexible sheet material, an 75 outer carrying ring to which the outer edge of said member is secured, and means for causing a relative approaching movement between said form and said ring, said shaping member being formed to resist the 80 outward pull thereon over the form caused by such relative movement between the form and said ring, whereby said shaping member is by such relative movement caused to press and stretch the hat material 85 against the form.

21. Hat shaping apparatus, comprising a brim form having an arched shaping face, means for heating said form, shaping means for co-operating with said form comprising 90 a sheet of porous flexible material adapted to bear against the material on the form and a carrier to which said sheet is secured, and means for causing a relative approaching movement between said form and said 95 carrier whereby the sheet is pulled against the form to press and stretch the hat material thereagainst.

22. Hat shaping apparatus, comprising in combination a hat shaping form having 100 a crown part and a brim part, means for stretching the crown portion of a hat body on the crown part of said form by engagement with the band portion of the hat body, and means formed to frictionally engage the 105 outer surface of the brim portion of the hat body to press the same against and stretch it outward on the brim part of said form after the crown portion of the hat body has been stretched.

110
23. Hat shaping apparatus, comprising in combination a hat shaping form having a crown part and a brim part, a band ring for engaging the band portion of a hat body to form the band angle and hold the 115 crown portion of the hat body stretched on the crown part of said form, an annular brim shaping member formed of flexible sheet material, a carrier for said member to which the outer edge thereof is secured, 120 means for causing a relative approaching movement between said form and said band ring and carrier and for bringing the band ring into operative position before the carrier brings the flexible shaping member 125 into operation.

24. Hat shaping apparatus, comprising in combination a hat shaping form comprising a crown part and a brim part, a clamping member for pressing the tip of a hat 130

body against the crown part of said form, means for stretching the crown portion of the hat body on the crown part of said form by engagement with the band portion of the 5 hat body after said clamping member has come into operation, and means for stretching the brim portion of the hat body outwardly against the brim part of said form.

25. Hat shaping apparatus, comprising a 10 brim form, means for clamping the hat material adjacent one edge of the brim form, a shaping member formed of flexible sheet material, and a member movable relatively to the brim form to stretch said shaping 15 member over the brim form in the direction away from said clamping means to shape the hat material thereon.

26. Apparatus for shaping hats, comprising a brim form, means for clamping the 20 hat material adjacent the inner edge of the brim form, a shaping member formed of flexible sheet material, and a carrying and tensioning member to which the outer edge of said shaping member is connected for 25 moving said member toward and tensioning it over said brim form.

27. The combination with a brim form having a transversely curved shaping face, of a coöperating annular flexible shaping 30 member having a broad operating face to bear against material placed on the form to be shaped, and means for causing a relative approaching movement between said form and said shaping member to press and 35 stretch the material to be shaped against the form.

28. The combination with a brim form, of means for coöperating therewith to shape a hat brim thereon comprising an annular 40 band of porous flexible sheet material, and a carrier to which the outer edge of said band is secured and by which it may be tensioned over said form.

29. The combination of a crown form support having upwardly extending side walls, means for heating said support, and a hollow crown form having on its inner side walls inwardly extending ribs whose edges are formed to contact with the side walls of 50 the support to receive heat therefrom.

30. The combination of a hat form support having a central upwardly extending portion and a surrounding laterally extending portion, means for heating the support, 55 and a hat form comprising a brim shaping part formed to seat on and receive heat from the laterally extending portion of the support and a hollow crown shaping part having its side walls formed to contact with the side walls of the upwardly extending portion of the support to receive heat therefrom.

31. The combination of a hat form support having a central upwardly extending 65 portion and a surrounding laterally exten-

ing portion, means for heating the support, a brim form seated on the laterally extending portion of the support and having heat conducting contact therewith, and a separate hollow crown form seated on the upwardly 70 extending portion of the support and having its side walls formed to contact with the side walls of said portion of the support to receive heat therefrom.

32. The combination of a hat form support having a central upwardly extending portion and a surrounding laterally extending portion, means for heating the support, a brim form seated on the laterally extending portion of the support and having heat 75 conducting contact therewith, and a separate hollow crown form having its bottom edge formed to contact with the brim form and its side walls formed to contact with the side walls of the upwardly extending portion of the support to receive heat therefrom.

33. The combination of a hat form support having a central upwardly extending portion and a surrounding laterally extending portion and formed with a chamber for receiving a heating fluid to heat both its upwardly extending portion and its laterally extending portion, and a hat form comprising a brim shaping part formed to seat on and receive heat from the laterally extending portion of the support, and a hollow crown shaping part having its side walls formed to contact with the side walls of the upwardly extending portion of the support to receive heat therefrom.

34. In a hat shaping machine, the combination with a press having opposed supporting members and means for moving one of said members toward and from the other, of a crown form support carried by one of said supporting members having upwardly-extending heat-transmitting form-supporting side walls, means for heating said support, and shaping means carried by the other supporting member for shaping a hat crown on a crown form seated on said crown form support.

35. In a hat shaping machine, the combination with a press having opposed supporting members and means for moving one of said members toward and from the other, of a hat form support carried by one of said supporting members having a central upwardly extending portion and a surrounding 115 laterally extending portion, means for heating the support, a brim form seated on the laterally extended portion of the support and having heat conducting contact therewith, a separate hollow crown form having 120 its bottom edge formed to contact with the brim form and having its side walls formed to contact with the side walls of the upwardly extending portion of the support to receive heat therefrom, and shaping means 125 130

carried by the other supporting member of the press comprising crown shaping means for engaging the band portion of a hat body on the crown form, and brim shaping means for stretching the brim portion of the hat body on the brim form.

36. A shaping member for coacting with a brim shaping form, said member being formed of an annular band of flexible and porous woven fabric having a tension resist-

ing inner edge and having a carrying ring secured to its outer edge.

In testimony whereof I have hereunto set my hand in the presence of two subscribing witnesses.

LESLIE STEVENS.
